Primary Examiner — Darlington Ly*Assistant Examiner* — Jessica Lynn Devilbiss(74) *Attorney, Agent, or Firm* — Nitin Kaushik(57) **CLAIM**

The ornamental design for a roof rack crossbar, as shown and described.

DESCRIPTION

FIG. 1 is a front perspective view of a roof rack crossbar, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and,

FIG. 10 is an enlarged detail view of area 10 in FIG. 2.

The broken lines in the drawings illustrate the portions of the roof rack crossbar, which form no part of the claimed design. The dash-dot-dash broken lines illustrate the periphery of the enlarged views of the roof rack crossbar and form no part of the claimed design.

1 Claim, 10 Drawing Sheets(56)
